TRANSMIT-RECEIVE SWITCH TUBE STRUCTURE

William J. Stanney, Needham Heights, and George W. Caley, Hamilton, Mass., assignors, by mesne assignments, to Sylvania Electric Products Inc., Wilmington, Del., a corporation of Delaware

Filed Mar. 12, 1958, Ser. No. 720,932

1 Claim. (Cl. 315—39)

This invention relates to gaseous discharge switching devices of the transmit-receive type, and more particularly to an improved structure and method of assembly of such devices.

Transmit-receive (TR) switching devices are employed in radio direction and ranging systems to permit the use of a common antenna for both transmission and reception of radio frequency energy. During transmission of the high power pulse from the transmitter, the device decouples the sensitive receiving apparatus by means of ionization of a suitable gas filling under reduced pressure contained within the envelope of the device. This decoupling action, together with the position of the TR switch in the system, insures that essentially all of the transmitted energy is directed to the antenna. Reflected radio frequency signals received by the same antenna are at too low a power level to cause ionization of the gas filling and are thus permitted to pass through the TR switch to the receiver.

Gaseous discharge switches of the TR type conventionally contain a mixture of gases, a necessary component of which is water vapor which serves as an electron capture agent. After cessation of a radio frequency discharge in the tube, free electrons remaining in the vicinity of the discharge gap cause a loss in intensity of the return low level signal. For satisfactory operation of the switch, therefore, it is necessary that these electrons can be removed from the gap. Water vapor is an effective electron capture agent, forming negative water vapor ions having low mobility which do not extract appreciable energy from the returning low level signal. The rate of removal of the free electrons, commonly known as "recovery time," is a critical characteristic of switches of this type, and is a determining factor in the minimum operating range and minimum target size of the radar system in which it is employed.

An auxiliary electrode is commonly employed in the TR switch to provide a source of electrons to aid in the ionization of the gas mixture within the envelope to promote a rapid discharge upon the incidence of a pulse from the transmitter. Such electrodes are now referred to in the art as the "keep-alive" or "ignitor" electrode. This electrode is introduced into the TR switch tube through an axial passage in a conical discharge gap electrode and is supported by the outer envelope of the tube. A direct current sustained glow discharge is maintained in the region extending from the tip area by biasing the ignitor electrode negatively with respect to the adjacent conical discharge gap electrode. Without the partial ionization of the discharge gap provided by the ignitor electrode sufficient amounts of radio frequency power to damage the receiving apparatus may be permitted through the TR switch before a gaseous discharge is initiated. It is, of course, desirable that the switch have such characteristics that the voltage required to initiate the direct current discharge will be constant over all operating conditions of the tube; for example, with increases in am-

bient temperature and life of the tube. The auxiliary direct current voltage supply for the keep-alive electrode is necessarily designed around specific current limits when incorporated in a radar system with the consequence that changes in characteristics of the gas in the discharge region may result in a sufficient variation in current to cause the glow discharge to be extinguished. It is common practice to employ the term "voltage drop" to define the difference in potential between the keep-alive electrode and the adjacent discharge gap electrode for a specified value of keep-alive current. Any increase or decrease in this voltage drop caused by changes in the characteristics of the gas in the discharge region will mean a corresponding inverse variation in current with a fixed voltage supply. A decrease in ignitor current could lead to: (a) relaxation oscillations of the discharge, with the consequence that the gap may not be ionized upon the incidence of a transmitted pulse, a condition which would allow higher leakage power to reach and damage the sensitive receiver; or (b) an increase in the power leakage characteristic of the device, a condition which would allow higher leakage power to reach and damage the sensitive receiver.

In the process of conducting investigations into various solutions to this problem, we have noted that when the ambient temperature of the tube is elevated, the gap resistance of the tube increases, the ignitor electrode voltage drop increases, and with a keep-alive voltage supply of fixed potential, the ignitor current decreases. We have theorized that this phenomena is caused by variations in the partial pressure of water vapor within the tube with changes in temperature. We have concluded that these variations in water vapor pressure result from the temperature-pressure characteristics of certain flux constituents which enter the effective volume of the tube while joining the parts thereof together with soft-solder.

During actual operation of the device under high peak power conditions, the partial pressure of water vapor also increases, thereby exposing the ignitor electrode to a more corrosive atmosphere than with lower water vapor pressure. Consequent deterioration of the ignitor electrode material causes a decrease in the effective area of the electrode, which, in turn, causes an increase in gap resistance and a corresponding decrease in ignitor current, creating the possibility of relaxation oscillations and causing increased power leakage with the attendant undesirable properties mentioned earlier. It therefore follows that the partial pressure of water vapor should be sufficient only to provide a satisfactory recovery time for the tube. Heretofore, in order to achieve a satisfactory recovery time in a new tube it has been necessary to employ a higher water vapor pressure than was required after a period of operation, with the obvious consequence of undue electrode deterioration with extended use.

In the assembly of a number of TR tube types, certain structural characteristics of the components of the tube require that the gas reservoir sub-assembly be soft-soldered to the body of the tube, this soft solder serving to hermetically seal the two parts together as well as providing a mechanical connection. Although this solder connection is quite remote from the discharge region, we believe that constituents of the flux make their way into the active volume of the tube at the time of soldering, where they are deposited as salts. These flux salts being hygroscopic compounds (zinc chloride and ammonium chloride), absorb some of the water vapor that is added to the basic fill gas of the tube, which is normally hydrogen or argon. Thus, after the tube is sealed off, the resultant partial pressure of water vapor is affected by and is in part determined by the presence and amount of hygroscopic salts present in the tube. Since, as was noted earlier, the re-

covery time characteristic of the switch is determined by the active water vapor within the gas volume, the initial recovery time characteristic of the tube is variable according to the water vapor pressure. Moreover, because the flux salts are hygroscopic, water vapor is released and absorbed according to the vapor pressure versus temperature characteristic of the compounds involved. Tests which we have conducted have shown that the pressure of water vapor increases with increased temperature, resulting in a lower recovery time. From what has been said earlier it is desirable that the recovery time be substantially constant over all conditions of operation of the switch and preferably as short as possible, in the range of 1.5 to 2.5 microseconds. It has been found, however, that these characteristics could not be achieved with tubes assembled with the soft soldering method described, recovery times in the range from 3.0 to 7.0 being about the best that could be achieved while still maintaining other electrical parameters constant. Coupled with an unsatisfactory recovery time, prior art tubes which have been soft soldered have also failed to meet rigid specifications, for example those established by the military, in respect to ignitor current drift with increases in temperature.

With an appreciation of the foregoing shortcomings of prior art TR devices, it is a primary object of the present invention to provide a transmit-receive gaseous switching device having stabilized electrical parameters at elevated temperatures.

Another object of the invention is to provide a transmit-receive device having a longer life during which the electrical characteristics of the tube are stable.

Still another object of the invention is to provide a transmit-receive gas switching tube having a low initial recovery time which does not appreciably change during the life of the tube.

These and other objects are attained in accordance with the present invention by means of a seal within the tube structure to protect the gaseous filling of the tube against the flux salts incident to the soft solder seal. This seal is made prior to the soft solder seal during the assembly process so as to eliminate the possibility of flux salts entering the active region during assembly. Preferably this seal is formed from a material which is sufficiently fluid to be readily applied in uniform fashion to the area to be sealed. For this purpose resinous compositions with cure or set as high melting or infusible materials, e.g., resins of the phenolic, polyester, or epoxy type, are particularly useful. Epoxy resins have been found eminently satisfactory because of their ease of application, their ability to withstand the operating temperatures of the tube, and their freedom from deleterious reaction products. The resinous material is applied to the area to be sealed prior to assembling the reservoir with the body portion, and upon curing prevents the entry of flux constituents into the active volume of the tube during the subsequent joining of the parts with soft-solder.

Other objects, advantages and features of the invention will be evident from the following detailed description when read in connection with the accompanying drawings, in which:

Fig. 1 is an elevation view, partially in section, of a commercially available TR tube (1B24A) showing the application of the invention thereto;

Figs. 2 and 2A are curves showing like characteristics of a tube of the type shown in Fig. 1 without and with the seal of the invention, respectively; and

Fig. 3 depicts curves showing the effect of the invention on the ignitor current versus temperature characteristic of the tube of Fig. 1.

Referring now to the drawings, Fig. 1 illustrates a transmit-receive device which is available commercially, and is referred to in the art as an integral cavity type. The main body of the tube comprises a pair of flanges, one of which is shown in the drawing at 10, joined to opposite

sides of a block of metal having a generally rectangular outer surface and a cylindrical axial passage therethrough. Spaced within the central portion of the axial passage, that is, at the section designated 12, and secured to the cylindrical wall are a pair of opposed conical discharge gap electrodes 14 and 16 having their large ends spaced apart to define therebetween a resonant cavity 18. The converging ends of electrodes 14 and 16 define between their opposing ends a discharge gap 20. Electrode 14 is normally of solid construction, whereas electrode 16 is hollow as shown, and has a small opening at its apex, into which the keep-alive electrode is inserted. Axial adjustment of the gap spacing to the frequency of operation may be made by deforming the flexible diaphragm on which electrode 14 is positioned with a suitable differential screw mechanism generally shown at 22 and disposed within the lower portion of the axial opening through the tube body. An exhaust tubulation 24 extends into the body member in the region of the discharge electrodes to communicate with the resonant cavity 18, and is utilized for evacuation as well as filling with the gas mixture under reduced atmospheric pressure. Discharge electrode 16 is held in place on a step on the axial bore by a circular member 26, the elements thus far described all being secured together by a hydrogen atmosphere brazing method which does not involve the use of flux. The TR switch is inserted in a wave guide system with the flanges 10 disposed perpendicularly to the longitudinal axis of the wave guide, and energy is transmitted into and out of the cavity portion 18 by a pair of coupling windows, one of which is shown at 28.

The other major portion of the switch, which is normally assembled as a sub-assembly and later joined with the body portion just described, is a reservoir for gas, 35 normally argon or hydrogen and water vapor. The reservoir comprises a glass bulb or envelope 30 to one end of which a metal tube 32 is joined with a suitable glass-to-metal seal. An ignitor or keep-alive electrode 34 is supported at one end by means of a glass-to-metal seal 36 to the upper end of the reservoir or bulb 30. Electrical contact to a direct current voltage supply and external circuitry may be made by means of top cap 38 sealed to the outer end of electrode 34. After assembly (the steps of which will be described hereinafter) the inner 45 tip of electrode 34 extends axially within the device through a passage 26a in disc 26 and into conical gap electrode 16 to a point a critically short distance from the apex of said electrode. Conventionally the ignitor electrode is insulatingly sheathed in glass except for its tip diameter.

The upper portion of the main body of the tube is normally provided with a cylindrical bore, designated at 40, of a diameter to receive the cylindrical tubing 32. Heretofore, the tube 32 was inserted into the bore 40 and 55 bottomed on disc 26 and thereafter sealed around the periphery by soft soldering. Exhaustive attempts have been made to substitute silver soldering for the soft solder at this seal without success due in large measure to the large quantity of glass in the reservoir bulb 30 and the danger of destroying the glass-to-metal seal between cylinder 32 and the glass envelope by the high temperatures involved with silver soldering. Heli-arc welding has also been attempted, but the costly equipment and additional assembly time indicated to be necessary for success have 60 made this approach prohibitive. Practical considerations therefore have dictated that the seal at 42 be made with soft solder, and it is the constituents of the flux used in making this seal that find their way into the active region of the tube to produce the deleterious results outlined above.

In accordance with the present invention, flux constituents from the soft-solder seal are prevented from entering the active volume of the tube by a second seal 44 applied prior to the making of the soft-solder joint. For ease of 75 application and to insure sealing against the flux constitu-

ents, resinous compositions which cure as high-melting or infusible materials are preferred in making the seal. Particularly useful for this purpose is a flexible epoxide casting resin known as "Stycast 2340 M" which is available from Emerson & Cuming, Inc., 869 Washington Street, Canton, Massachusetts. "Stycast 2340M" is a two-part casting resin requiring no catalyst addition, the two components of which are simply mixed and cured to produce an opaque resin which is extremely tough while quite flexible. It adheres very well to metals, plastics, and glass.

In the assembly of the TR tube in accordance with the invention, the two components of the resin as received from the manufacturer are mixed to produce a flowable plastic mass which, for convenience of application, is inserted in a squeeze tube having a long spout. The tip of the spout is inserted into the bore 40 and bead of the plastic material applied around the periphery of disc 26 where it joins the wall of the bore. Thereafter, before the resin has set, cylinder 32 of the reservoir sub-assembly is inserted into the bore and seated on the disc 26, the resin flowing around the lower end of the cylinder 32 to completely seal the two parts together at this point. To cure the resin, the assembled tube is placed in an oven at a temperature of about 150° F. for a period of 8 to 10 hours. The resin cures tack-free, is very tough, and has been found to provide an hermetic seal between the cylinder 32 and the body portion of the tube. However, to improve the ruggedness of the tube, the cylinder is preferably also soft-soldered to the body portion at 42 after the resin has set. It will be noted, however, that with the soft-soldering operation following the making of the resin seal, flux constituents which may flow into the space between tube 32 and bore 40 during the application of the solder cannot reach the cavity 18 or the gas reservoir 30, 32. The favorable properties of this resin outlined above are retained over a temperature range of -40° C. to +150° C. with the consequence that the sealing properties are retained over the normal operating temperatures of the tube and therefore protect the cavity 18 from flux constituents throughout the life of the tube.

That the provision of the epoxy resin seal is effective to stabilize the electrical characteristics of a transmit-receive switch will be evident from an examination of Figs. 2 and 2A which are plots of certain electrical characteristics of a 1B24A tube, without and with the seal, respectively. A longer test was performed on the tube with the seal so the curves do not give a full direct comparison, but the curves of Fig. 2A emphasize that the characteristics are improved over the first 500 hours of life and that these characteristics are maintained for considerable longer periods. The curves are those conventionally used to indicate TR tube performance and are as follows:

E_{id} =ignitor voltage drop

P.L.=peak leakage power

L_i =insertion loss

ΔL_i =increase in insertion loss when keep-alive voltage is on

The ordinates of the graphs of Figs. 2 and 2A have not been labeled, the significance of the numbers being as follows: ignitor voltage drop is measured in hundreds of volts; peak leakage power is measured in tens of milliwatts; insertion loss is measured in db, and the increment in insertion loss, ΔL_i , is measured in tenths of a db.

Considering first the curves of Fig. 2, it will be noted that without the seal the ignitor voltage drop increases in value from about 340 volts to approximately 475 volts over the 500 hours of operation. Some variation is also noted in the peak leakage power and it will be noted that there is a considerable increase in ΔL_i when an increase in E_{id} was observed. The recovery time of the "unsealed" tube was not tested, but in general it had been observed on tests of many tubes manufactured without the seal that

the recovery time varied between 3.0 and 7.0 microseconds, and stayed fairly constant throughout the life of the tube.

The improvement afforded by the seal will be readily evident from Fig. 2A wherein it is seen that the ignitor voltage drop was substantially constant at approximately 380 volts throughout the 1000 hours of the life test, the peak leakage power was of the same order of magnitude as without the seal but was more constant throughout the life of the tube, and the incremental insertion loss when the keep-alive is energized is substantially less and essentially constant over the life of the tube. The recovery time of the tube with the seal was measured, and the plot indicates that the initial recovery time was slightly less than 2 microseconds and remained at that value for approximately 500 hours of life at which time it dropped slightly.

The curves of Fig. 3, which show the effect of variations in temperature on the ignitor current, also clearly illustrate the advantage obtained with the seal. In tubes without a seal, the ignitor current dropped in value from about 80 microamperes to approximately 60 microamperes, over a temperature range from 20° C. to 120° C., whereas in tubes with the seal the ignitor current was essentially constant over this range. This constancy of current prevents the relaxation oscillator characteristics of the discharge which often occurs when the ignitor current falls off due to increase in temperature.

Having discovered and explained the reasons for certain untoward effects in prior art TR tubes, and having disclosed a specific embodiment of means for eliminating these effects in a particular tube type, the application of the invention to other TR types and other discharge devices when the flux problem exists will now be apparent to ones skilled in the tube art. Also, having suggested a specific resin for making the seal and outlining its desirable properties, other satisfactory sealing materials will be apparent to those skilled in the resin art. Accordingly, the invention need not be limited to the specific details illustrated and described but should be regarded as subject only to the limitations of the appended claim.

What is claimed is:

A method for assembling a transmit-receive gaseous discharge device of a type having a body portion provided with an internal cavity and a bore communicating with the cavity, and a gas reservoir including a glass bulb and a metal tube insertable in said bore, comprising the steps of: applying around the bottom of said bore a bead of fluid epoxy casting resin which upon curing forms a high-melting, flexible resinous material, inserting said tube into said bore to engage said bead of resin, curing the assembly at a suitable temperature and for a period to cure said resin whereby to form an hermetic seal between the inner end of said tube and said bore which does not release harmful constituents into said cavity, and thereafter soft soldering said tube to said body portion at the outer end of said bore, the seal formed by the resin precluding the entry into said cavity of harmful constituents of the flux employed in the step of soft-soldering.
